UNITED STATES PATENT OFFICE.

MATTHEW B. SELLERS, OF BALTIMORE, MARYLAND.

AERIAL NAVIGATION.

1,096,129.

Specification of Letters Patent. Patented May 12, 1914.

Application filed August 8, 1912. Serial No. 714,081.

To all whom it may concern:

Be it known that I, MATTHEW B. SELLERS, a citizen of the United States, and resident of Baltimore, Maryland, have invented a 5 new and useful Improvement in Aerial Navigation, of which the following is a specification.

This invention is an improvement in aeroplanes, and particularly on the one described in my patent of July 11 1911 No. 997,860: the improvement being in connection with the steering and running gear therein described.

In the drawing, Figure 1 is a side elevation of a portion of the aeroplane described in my patent referred to, showing the application of the new device for releasing the wheels. Fig. 2 is a front view of the catch shown in Fig. 1. Fig. 3 is a detail view 20 showing part of the wheel frame. Fig. 4 is a plan view of the rear part of the wheel frame showing the whole detent mechanism. Fig. 5 is detail section of the loop. Fig. 6 is the rear elevation of the string gear as 25 now used.

As stated in my patent referred to, the wheels of this machine are held below the runners or skids during the preliminary run by a suitable detent means, which is afterward automatically released allowing the machine to alight on the skids; and this can be done in various ways. The releasing device herein described seems by long trial to be the best. The detent means here em-

ployed is here shown in Fig. 4, which shows the rear portion of the front wheel frame, being similar to that shown in Fig. 5 of the previous patent; and, as there designated, W, W¹, are the wheels; U and U¹ the frame 40 for each wheel, T² the bar connecting them, while P P¹, and T³ are part of the body frame. When the wheels are down as here shown, the loops L and L¹ on the main frame bars P and P¹, project through holes 45 in the cross bar T as shown in detail section in Fig. 5. The pins I and I¹ on the lever J, engage these loops as shown in Fig. 4; and the loop F, engaging the eye K, holds the lever in this position, against the pull of

50 the spring S. When the hook F, is withdrawn, the lever J, is thrown back withdrawing the pins and permitting the wheel frame to rise as shown in Fig. 3. The wheel frame can then be drawn up by a spring, or 55 forced up by contact of the wheels with the ground. The automatic device for with-

drawing the hook, and releasing the wheels, is shown in Fig. 1, which is a side elevation of a portion of the machine described in the previous patent. The wing B, corresponds to the wing B, in Figs. 1 and 2 thereof, and is supported by the inclined strut E. The post G, extending from this strut to the chassis as shown. The front wing spar B, is attached to the strut, and the rear spar is 60 supported by the prop M, which is free to move up and down about one inch, and is normally held down by the spring C. The lever A, is pivoted at A¹ and one end of it passes through an eye affixed to M, while the other end is in contact with the catch D, shown in Fig. 2. A wire from this catch runs down to a lever F, operating the hook F. Now the spring C, is so adjusted that the air pressure due to the propeller blast, 65 together with that due to forward motion suffices to raise the wing B and the post M, as far as it will go and hold it there. The end of lever A, will then engage the tooth H, Fig. 2. When however the propeller is 70 stopped, the pressure on the wing is diminished and the prop M, descends; the lever A, will raise the tooth H, and therefore the hook F, releasing the wheels. A similar device can also be used to actuate any other 75 mechanism provided that its action coincides with a variation in air pressure on the wing.

The steering gear described in the previous patent Figs. 14, 15 and 16, comprised 80 a horizontal handle bar on a vertical post, with a forwardly projecting arm. The bar was rotated for "elevating"; and turned in a horizontal plane, for warping and steering. It was soon found unsatisfactory to 85 combine warping and steering in one motion, and the modification herein described was found to give the best results, this is shown in detail in Fig. 6. The steering bar is journaled in the tube 4, which is rigidly 90 attached to the block 2, pivoted at 3 on the post 1, which is journaled at its ends. To the steering bar 5, is affixed the drum 7; and the block carries the upwardly projecting arm 8, having the two guide pulleys at its 95 upper end. The cords 9, 9¹, are fastened to the drum, pass over the guide pulleys 10; and lead to the top plane in the manner described in the previous patent, and there shown in Figs. 1 and 12 at Y². If now the 100 drum is rotated backward the cords 9, 9¹, are 105 tightened thus increasing the angle of at-

tack of both sides (or wings) of the top plane, causing the machine to incline upward; and vice versa. If however the handle bar is tipped or inclined sidewise as shown, the cord 9 is tightened, while 9¹ is correspondingly slackened, thus increasing the angle of one wing while diminishing that of the other; (controlling lateral stability). The lines from the rudder run to the ends of the steering bar as before. In the machine (quadraplane) described, the forward and highest plane acts as an elevator and lateral stabilizer as just stated; but in a similar machine with two planes a separate elevator is desirable; in which case the line from the elevator is led directly to the drum from a fixed guide pulley; while the lines 9 and 9¹, are attached to the end of arm 8. The steering device herein described is made the subject of my application No. 749412—filed Feb. 9, 1913.

I claim.

1. In an aeroplane having wheels and skids and a detent means holding the wheels in a lowered position; a device for actuating said detent means comprising a wing or portion thereof adapted to rise a limited distance under the pressure of the air in flight, a spring depressing said wing when the pressure is reduced, a lever suitably connected with said wing and engaging a catch when said wing is raised, and actuating the catch when the wing is depressed, connection between the catch and the detent means substantially as described.

2. In an aeroplane having skids and wheels, a detent means for releasing the wheels, and an automatic device for actuating said detent means comprising a wing or portion thereof, adapted to rise a limited distance under pressure of the air in flight, a spring depressing the wing when said pres-

sure is reduced a catch, means connected with the wing, and engaging the catch when the wing is raised, and actuating the catch when the wing is lowered, connection between the catch and said detent means.

3. In an aeroplane having skids and wheels and a detent means holding the wheels in a lowered position; a device for actuating said means comprising a wing or portion thereof adapted to be raised a limited distance under pressure of the air in flight; a spring depressing the wing when said pressure is reduced; a catch engaged when the wing is raised, and actuated when the wing is depressed; connection between the catch and the detent means.

4. In an aeroplane, a wing or portion thereof adapted to rise a limited distance under the pressure of the air in flight; a spring depressing said wing when the pressure is reduced, a catch a lever suitably connected with said wing and engaging the catch when the wing is raised, and actuating the catch when the wing is depressed, a mechanism to be actuated, suitable connection between the catch and said mechanism to actuate the same.

5. In an aeroplane a wing or portion thereof adapted to rise a limited distance under the pressure of the air in flight, a spring depressing said wing when the pressure is reduced, a catch, a lever suitably connected with said wing, adapted to engage the catch when the wing is raised; and to actuate the catch, when the wing is depressed, substantially as described.

Signed in presence of two subscribing witnesses.
